UNITED STATES PATENT OFFICE.

WILLIAM WRIGHT, OF CHICAGO, ILLINOIS, ASSIGNOR TO E. PAYSON SMITH, OF SPRINGFIELD, ILLINOIS.

CONNECTING BAR.

Application filed August 15, 1925. Serial No. 50,529.

My invention relates to connecting bars employed, more especially, in connecting the brake levers of railway trucks, or for use as push rods for brake cylinders and other similar purposes; the invention relating to the construction of a connecting bar and more specifically to the formation of the pin eyes or holes where the greatest amount of wear is encountered. That is to say, my invention has for its object the provision of independent bearing surfaces or bushings for the pins, whereby the bar is connected to the usual brake operating mechanism or other supporting elements, in order that these bearing surfaces or bushings after same have become worn may be readily removed and renewed, thereby obviating the necessity for renewing the entire bar as, however, is the case with connecting bars as at present employed.

The construction of truck lever connections or connecting bars as light as possible, commensurate with the strength necessary for compression bars of this type, has been the object of recent developments. As a result, bars of the type in question have frequently been made of pressed or sheet metal steel, given various configurations or shapes in cross section in order to provide a maximum of strength and stiffness so as to withstand the compression strains and stresses. Making the bars of comparatively thin metal, results in the bifurcated or forked ends having too little metal where the pin holes are provided and where wear is encountered by the frictional engagement with the pins. In practice it has been found that the pin receiving holes soon become enlarged which results in undue play and lost motion and also often resulting in breakage at these points, especially with constructions where the metal has been up-set or drawn about the holes in an effort to provide larger bearing surfaces for the pins than would be afforded by the normal thickness of the bifurcated portions of the bar; such constructions resulting in an attenuation of the portions intermediate of the holes.

The purpose of my invention is to enable the use of connecting bars which are comparatively light in weight (a desideratum in present railway construction) but which possess strength and rigidity and at the same time are reenforced at the pin receiving holes to withstand the strains and stresses, but

which reenforcement may be removed and renewed when occasion requires without, however, requiring renewal of the entire connecting bar, with the result that the life of connecting bars involving my invention is greatly enhanced.

The objects and advantages of my invention will be fully comprehended from the following detailed description of the drawing, wherein—

Figure 1 is a side view of a connecting bar embodying my invention.

Figure 2 is an enlarged plan view of one end of my improved bar.

Figure 3 is a perspective view of one end thereof.

Figure 4 is a plan view of one end of a blank from which the bar is formed, namely before the blank is shaped into the desired cross-sectional configuration.

Figure 5 is a cross-sectional view taken substantially on the line 5—5 of Figure 1 looking in the direction of the arrows.

Figure 6 is a cross sectional view taken on the line 6—6 of Figure 1 looking in the direction of the arrows.

Figure 7 is a side view of a modified form of my improved connecting bar.

Figure 8 is a detail sectional view illustrating a modification of the renewal bearing member or bushing.

Figure 9 is a similar view illustrating another modified form of bearing member or bushing.

In the particular exemplification of my invention as disclosed in the first six figures of the drawing, the connecting bar consists of a main body portion 10 formed of pressed steel or other suitable metal and having a cross sectional configuration when formed into shape adapted to provide rigidity; the bar being preferably given the channel formation more clearly shown in Figure 3. The bar is preferably formed from a metal plate or blank shown at 11 in Figure 4, of requisite length and width, with both ends of the blank slit or cut away as at 12 to provide the bifurcations or ears 13, 13.

The ears 13 are all provided with suitably spaced holes 14 (any desired number); with the holes in the two ears at each end of the blank arranged to be in alignment or register when the blank has been pressed or formed into a completed bar. The holes 14 are so arranged with respect to the marginal

edges of the blank, that the marginal edges of the bifurcations or ears, like the marginal longitudinal edges of the main portion of the blank may be turned or flanged as shown at 15, see Figure 3. The flanges are preferably formed to be in opposition, namely disposed inwardly toward each other as shown: it being understood that both marginal edges of each ear or projection 13 is similarly flanged, thereby giving the ears strength and rigidity. The metal at the base of the slit 12 is also preferably upset so as to constitute a continuation of the flange 15 of the ears about the base of the slits as shown in dotted lines at 16 in Figure 2.

With the blank formed in the manner shown and described, it is apparent that a very rigid bar is provided adapted to withstand the compression strains to which connecting bars are subjected, while at the same time employing a modicum of metal, relatively speaking, commensurate with the strength necessary.

The various pin receiving holes 14 are provided with suitable bearing members, preferably in the nature of case hardened bushings 17. The bushing shown in Figure 5 is in the nature of a thimble of relative thickness, being preferably somewhat heavier or thicker at one end as shown at 18, while the other end is somewhat thinner so as to snugly pass through the holes 14 in the ears or bifurcations 13 of the bar. The thimbles or bushings are inserted into the holes so as to bring the shoulder formed by the enlarged end 18 up flush against the sides of the ears and preferably on the inner sides of the bifurcations as shown in Figure 5. The reduced or smaller end of the thimble is then upset or swaged outwardly to overlap the perimeter of the holes in the ears as shown at 19 in Figure 5, thereby firmly fastening or clamping the bushing in place.

As is apparent from the construction shown, a comparatively heavy and wide bearing surface for the pin is provided, namely a surface of materially greater thickness than would be afforded by the bifurcations or ears themselves and therefore a surface adapted to withstand the wearing strains and stresses encountered between the pins and the connecting bar.

In Figure 8 I show a modified form of the bushing, consisting of a thimble or band of equal thickness throughout; which, after having been inserted in the hole in the ears or bifurcations, preferably has the inner end turned over outwardly upon itself as shown at 20. The outer end of the band is then swaged outwardly about the perimeter of the hole in the ears as shown at 21 thereby firmly holding the bushing in place. This provides a bearing surface for the pin of materially greater width than the thickness

of the metal forming the connecting bar and its ears or bifurcations.

In Figure 9 I show another method of providing a wide bearing or bushing for the pins, consisting in a thimble of substantially the same initial formation of the bushing 17 shown in Figure 5 before the outer end was upset or swaged. The bushing 22 in Figure 9, instead of having the reduced or thinner end swaged, is externally threaded as shown at 23 and the ear or bifurcation of which only a portion is shown at 24 is provided with a tapped or threaded opening adapted to receive the threaded end of the bushing 22, which may be screwed into place after the bar has been completely formed.

With all of the constructions shown and described it is apparent that a greater bearing surface is not only provided for the pins, but these bearing surfaces or bushings may all be removed after becoming worn beyond a desirable degree and new bushings of similar type inserted thereby obviating the necessity of renewing the bar itself. As a result the working life or usefulness of the connecting bar is greatly enhanced and a material saving in labor and expense obtained.

In Figure 7 the construction and formation of the connecting bar 10^a is substantially the same as that previously described, except that the ends 13^a are offset or bent at an angle to the axis of the body portion to meet certain requirements and the ends are shown provided with a lesser number of pin receiving holes although any desired number may be employed, which, however, are provided with my improved bearing surfaces or bushings, which may be either of the types shown and described.

The blank or cut sheet of metal, of which a portion or one end is shown in Figure 4, has its marginal edges bent or flanged as shown at 15 and 16 and the flanged sheet is then bent into the channel formation shown with the longitudinal flanges 15 spaced the same distance apart, substantially, throughout the length of the bar; with the base or intermediate portion of the channel preferably slightly dished or concaved as shown at 25 in Figure 6. Forming the base of the channel in the manner shown prevents undue strain of the metal while forming, while at the same time providing the strength and rigidity of a beam construction adapted to withstand compression strains.

The constructions illustrated are believed to be the simplest embodiments of my invention, but modifications are possible and may be made, without, however, departing from the spirit of my invention.

What I claim is:

A connecting bar, adapted to be secured in place by means of pins, formed of sheet

metal of uniform dimensions throughout and pressed into channel formation, the ends being slit longitudinally to provide a pair of ears at each end, the marginal edges of the sheet and its ears being bent toward each other with the marginal edge of the metal at the base of the ears being bent outwardly,

the ears being provided with registering pin receiving holes, and removable bushings of comparatively thick metal and of length ¹⁰ greater than the thickness of the sheet metal inserted in said holes to provide large bearing surfaces for the connecting bar pins.

WILLIAM WRIGHT.
